UNITED STATES PATENT OFFICE

JOSEPH AMON, OF RAHWAY, NEW JERSEY

THREAD-MOISTENING DEVICE

Application filed July 15, 1929. Serial No. 378,505.

The present invention appertains to new and useful improvements in textile finishing, and more particularly to a novel device for moistening threads in the operation of finishing the same.

The principal object of this invention is to provide a moistening device wherein the thread may be moistened in a convenient manner and payed off without necessitating intricate mechanism.

Another important object of the invention is to provide a moistening device of the character mentioned wherein the liquid supply may be replenished when desired without interfering with the thread under treatment.

Various other important objects and advantages of this invention will become more apparent to the reader after considering the invention as described and claimed herein-after.

In the drawings:

Figure 1 represents a front elevation of the novel cabinet structure.

Figure 2 represents a longitudinal vertical sectional view through the cabinet.

Figure 3 represents a horizontal sectional view through the cabinet.

Figure 4 represents a vertical transverse sectional view through the novel structure.

Figure 5 represents a side elevation of one of the sliding closures, partly broken away to disclose the manner of retaining the transparent pane.

Figure 6 represents an enlarged fragmentary sectional view through a portion of the cabinet.

Figure 7 represents a side elevation fragmentarily showing one corner of one of the closures.

Referring to the drawings wherein like numerals designate like parts, it will be seen that this invention includes a rectangular shaped casing 5 provided at its longitudinal sides with rectangular shaped openings. Beneath the opening at one side of the casing is another opening extending longitudinally of the casing for receiving the drawer 6, which drawer is provided at its outer end with a handle 7.

Immediately above the drawer compartment of the casing a flange 8 projects inwardly from the vertical wall and is reinforced at its edge by being pressed backwardly. A pair of tray sections 9-9 are flanged at their edges as at 10 for rest upon the flange 8. Each section is provided with a plurality of openings 11 and arranged in a suitable manner between these openings are pintles 12 for supporting spools of thread.

The vertical edge portions of the rectangular openings in the longitudinal side walls of the casing are bent outwardly as at 13 and laterally as at 14, the edge portion of the lateral portion 14 being bent backwardly as a matter of reinforcement. Upper and lower frame pieces 16 and 17 respectively are provided for each side wall opening, the lower frame piece 17 consists of an elongated trough shaped construction with its inner edge portion bent for disposition over the upper edge of the vertical plate 18 extending from the flange 8 (see Figure 4). The outer edge of the framewise 17 is pressed backwardly to reinforce the same.

The framewise 16 is comparatively deeper than the frame piece 17, and is substantially U-shaped in cross section. The inner edge portion of the frame piece 16 is bent as at 19 for overlapping engagement with the upper edge portion of the opening, while the outer edge of the frame piece is pressed backwardly to reinforce the same. It will be seen that the same frame construction is provided for each opening of the casing, excepting that the lower frame piece 17 of the backwall has its inner edge portion overlapping the edge portion of the rear wall instead of the upstanding plate 18 as at the front side of the casing. The presence of the drawer necessitates such a construction.

Horizontally slidably within each frame are the sliding sashes generally referred to by 20. Each sliding sash consists in construction of a rectangular frame including sides and bottom pieces 21-21 and 22 respectively. The upper connecting piece 23 is longitudinally slotted to receive the transparent panels 24. Each of the side pieces 21-21 as well as the bottom piece 22 is of U-shaped

cross section to provide a guideway for the edge portions of the pane 24. The outermost end of one of the sash frames is provided with a vertical rod 25 suitably secured thereto, (see Figure 5).

It will be seen that the sashes are provided with handles 26 and that the ends of the upstanding plate 18 and the lower edge portion of the opening in the rear side of the casing are bent into the lower frame pieces 17, in the manner shown in Figure 6 and denoted by numeral 27, to constrict the passageway at this point, so that the end of the sash engaging therein will bind. Obviously, should one of the panes 24 become broken, the particular sash may be easily removed by lifting the sash so as to move its upper end upwardly within the upper frame piece 16 and disengaging the lower portion of the sash from the frame piece 17.

After removing the sash completely from the cabinet, the same may be inverted, and the pane 24 will readily slip therefrom. A new pane may be replaced, and by first inserting the upper end of the sash within the upper frame piece 16 and then moving the sash inwardly to assume a vertical position, the same may be lowered so that the lower portion of the sash will drop into the lower frame piece 17.

In Figure 7, it will be seen that the overlapping ends of the sash frames are provided with bearing strips 28 to resist wear and provide a snug fit when the sashes are in closed position.

The top wall of the casing has a plurality of openings therein and within each opening a guide bushing 29 may be disposed for receiving thread being payed from the spools on the pintles 12. The drawer 6 is to contain liquid from which a vapor rises through the opening 11 to moisten the thread.

A suitable latch 30 is provided on the front side of the casing at each end of the front side of the drawer 6 and these may be engaged against the drawer in the manner shown in Figure 1 to prevent the accidental displacement thereof.

It will be noted that the foregoing specification is in specific terms and it is to be understood that in the manufacture of this novel cabinet structure, various changes in the shape, size and materials may be resorted to without departing from the spirit and scope of the invention as claimed herein-after.

Having thus described my invention, what I claim as new is:

1. A thread moistening device comprising a cabinet normally open at its bottom and having closures mounted in its sides, a drawer mounted to slide in guides at the open bottom of the cabinet and to contain a liquid, said cabinet having an inwardly projecting flange immediately above the drawer, a pair

of trays resting upon the said flange and provided with pintles for supporting spools of threads and perforated to provide openings through which the vapor of the liquid arises to moisten the thread, and a plurality of guide bushings disposed in the top wall of the cabinet to provide guides through which the thread of the spool is adapted to extend.

2. A thread moistening device comprising a cabinet normally open at its bottom and having transparent slideable side closures, a drawer mounted to slide in guides at the open bottom of the cabinet and normally closing the said bottom, said drawer being adapted to contain a moistening liquid, said cabinet having an inwardly projecting flange formed integral therewith immediately above the drawer, a pair of trays resting upon the said flange and serving as a cover for the said drawer, said trays being respectively provided with pintles for supporting spools of thread, and perforated to provide openings through which the vapor of the liquid arises to moisten the thread, and a plurality of guide bushings disposed in suitable openings in the top walls of the cabinet to provide guides through which the thread of the spools is adapted to be fed.

In testimony whereof I affix my signature.

JOSEPH AMON.
